UNITED STATES PATENT OFFICE.

VADEN S. STEPHENS, OF MARSTON, MISSOURI.

WINDMILL.

1,168,975.

Specification of Letters Patent.

Patented Jan. 18, 1916.

Application filed November 15, 1913, Serial No. 801,309. Renewed December 1, 1915. Serial No. 64,579.

To all whom it may concern:

Be it known that I, VADEN S. STEPHENS, a citizen of the United States, residing at Marston, in the county of New Madrid and State of Missouri, have invented certain new and useful Improvements in Windmills, of which the following is a specification, reference being had to the accompanying drawings.

10 This invention relates to new and useful improvements in wind mills, the object of the invention being to provide a wind mill wherein the operating shaft is mounted within a suitable housing which in turn is 15 mounted for rotation upon the upper end of the derrick, said device being further provided with a hinged rudder which may be readily swung to an inoperative position when the mill is not in use so as to stop the 20 operation of the pump.

Another object of the invention is the provision of a wind mill of the above character which will possess advantages in points of efficiency and durability, is inexpensive of 25 manufacture and at the same time is simple in construction and operation.

With the above and other objects in view, the invention consists in the novel features of construction and the combination and arrangement of parts to be hereinafter more 30 fully described, pointed out in the claim and shown in the accompanying drawings, in which—

Figure 1 is a top plan view; Fig. 2 is a 35 side elevation, parts thereof being shown in cross section; Fig. 3 is a detail side elevation of the rudder bar illustrating the mounting of the same.

Referring more particularly to the drawings, 1 indicates the derrick which may be of any well known construction and is provided at its upper end with a suitable platform 2 upon which is rotatably mounted the housing 3, said housing being mounted upon 45 roller bearings 4 whereby the housing may be readily rotated upon the platform 2. The housing may be either circular or rectangular in form and is provided with an open upper end having a removable cover 5 mounted thereon to keep the rain and dirt from the interior of the housing.

Mounted for rotation within the housing 3 is a crank shaft 6, said crank shaft being 50 rotatably mounted within suitable bearings 7 formed in the side wall of the housing and the end portions thereof projecting out-

wardly beyond the outer wall of the housing. Mounted upon one end of the crank shaft 6 is the wind wheel 8 which may be of any ordinary construction and mounted upon the 60 other end of the crank shaft is a governor 9 which is adapted to regulate the speed of the wheel according to the velocity of the wind. The intermediate portion of the shaft 6 is provided with a suitable crank 65 which is connected to the upper end of the pitman 10 whereby upon the rotation of the shaft 6, the pump will be actuated through the medium of the pitman 10.

The pitman 10 is reciprocated adjacent its 70 upper end within a suitable casing 11 which is suspended from the bottom of the housing 3. The rudder 12 is provided with a suitable supporting bar 13, the inner end of which is hingedly secured to the outer wall 75 of the housing, as shown at 14, and is normally retained in a horizontal position by means of a spring member 15, the intermediate portion of which is arranged beneath the bar 13 and bears against the same to normally 80 retain the rudder in a horizontal position. The ends of the spring member 15 are passed over the pintle 14 and thence extended downwardly and secured to the outer wall of the housing, as shown at 16. From 85 this it will be noted that when the downward pressure is applied to the rudder, the spring 15 will be placed under tension so that when the rudder is released, the tension of the spring will return the same to its normal 90 horizontal position.

From the above description taken in connection with the accompanying drawings, it will be readily apparent that I have provided a wind mill of the above character 95 which is extremely simple in construction and effective in its operation. It will be noted that by having the housing 3 mounted upon the roller bearings 4, the housing may be readily rotated and that by having the 100 crank shaft arranged within the housing, the same will be fully protected against the weather so that all liability of its becoming rusted or otherwise placed in an inoperative condition is eliminated. In order to 105 move the rudder 12 to an inoperative position, I provide a cord or wire 17, the upper end of which is secured to the rudder while the other end thereof extends downwardly along the derrick and can be actuated from 110 the ground. Thus when it is desired to place the rudder in an inoperative position, the

wire 7 is pulled downwardly so that the rudder may be disposed in a substantially vertical position and as soon as the wire is released the tension of the spring 15 will readily return the rudder to its normal position.

It will be noted from the illustration in Fig. 1 that the wheel 8 is facing the direction of the wind and when the rudder 12 is swung downwardly to an inoperative position, the wind will bear against the auxiliary rudder 12' and rotate the wheel 8 around to an inoperative position, but when the rudder 12 is returned to its normal position, the wheel 8 will be returned to its operative position, that is, facing the direction of the wind so that the shaft 6 will again be rotated and the operation of the pump resumed. It will be noted that by providing the auxiliary rudder 12', the wheel 8 when the rudder 12 is placed in an inoperative position will also be turned to an inoperative position.

While I have shown and described the preferred form of my invention, it will be obvious that various changes in the details of construction and in the proportions may

be resorted to for successfully carrying my invention into practice without sacrificing any of the novel features or departing from the scope of the appended claim.

What I claim is:—

A device of the class described including a derrick having a platform at the upper end thereof, a housing rotatably mounted upon the derrick, roller bearings disposed between the housing and the platform, a crank shaft rotatably mounted within said housing and having a pitman connected thereto, a wind wheel mounted upon one end of said shaft, a rudder having its inner end hingedly connected to the housing, a spring member having its medial portion bearing against the under side of the rudder and its ends extended over the pintle portion of the hinge and thence downwardly and secured to the housing whereby the rudder will be yieldably retained in its normal position.

In testimony whereof I hereunto affix my signature in the presence of two witnesses.
